UNITED STATES PATENT OFFICE

JEREMIAH A. JANISSE, OF DETROIT, MICHIGAN

TIE

Application filed August 4, 1928. Serial No. 297,416.

The present invention pertains to a novel tie of the made-up type, and the principal object is to provide a tie of this character which is practically indestructible and which may 5 readily be cleaned or washed. Such a tie is designed for use by uniformed persons, such as chauffeurs, motor cycle policemen, mail carriers and other workers whose calling requires a neat attire. In such occupations the 10 clothing readily becomes soiled, particularly the neckties, which consequently must be cleaned or replaced at short intervals.

This invention provides a leather tie fabricated to have an appearance resembling 15 cloth but considerably more durable than any of the ordinary fabrics. Having a smooth finish, the tie of leather or leather substitute does not readily become soiled, but if soiled it may easily be cleaned, simply by the use of a 20 damp cloth.

The invention is fully disclosed by way of example in the following description and in the accompanying drawings in which—

Figure 1 is an elevation of the tie;

Fig. 2 is a top plan view thereof;

Fig. 3 is a rear elevation of one of the strips constituting the tie;

Fig. 4 is a section on the line 4—4 of Fig. 3; and

Fig. 5 is a transverse section of a modified form of tie.

Reference to these views will now be made by use of like characters which are employed to designate corresponding parts throughout.

The body of the tie is comprised of a pair of similar strips 1 of leather or substitute leather material having the outer surface finished in black or any other suitable color or design. The edges of these strips are skived 40 as at 2 and folded back and glued as at 3 upon the rear or unfinished side of the material as shown in Figs. 3 and 4. The strips are of substantially rectangular configuration and between the longitudinal edges thereof are caused to be concaved as at 4 midway between the ends when finished.

The strips are superposed as shown in Fig. 2, and a loop 5 of similar material is tied around them over the concaved edges 4. The 50 loop is tightened around the strips in such

a manner as to wrinkle the material between the edges 4, as indicated by the numeral 6, whereby the material at the sides of the loop takes the formation of wings or bats 7 common in bow ties. The ends of the loop are 55 stitched together as at 8 at the back of the strips and serve to hold one end of a neck band 9 carrying a loop 10 engageable by a hook 11 at the other end of the band. This band may be of elastic material and of the 60 adjustable type ordinarily used with made-up bow ties.

In Fig. 5 is illustrated a modification wherein the loop 5 is replaced by a metal clip 12 previously covered with a thin strip of material 13 similar to the material constituting the main strips 1. By means of a suitable tool, the ends 14 of the covered strip 12 are bent into the wrinkled portion 6 whereby to hold the strips 1 in the condition illustrated 70 in Fig. 1.

Although specific embodiments of the invention have been illustrated and described, it will be understood that various alterations in the details of construction may be made 75 without departing from the scope of the invention as indicated by the appended claim.

What I claim is:—

A tie comprising a strip of fibrous material of substantially rectangular formation and 80 having its longer edges concaved, and a covered metal clip tied transversely around said strip, over said concaved edges, and wrinkling the material between said edges, the ends of said clip being bent into the wrinkled 85 portion of said material.

In testimony whereof I affix my signature.
JEREMIAH A. JANISSE.
